UNITED STATES PATENT OFFICE

ALFRED F. C. LOTZ, OF CHICAGO, ILLINOIS, ASSIGNOR TO ELECTRICAL ENGINEERS EQUIPMENT CO., OF CHICAGO, ILLINOIS, A CORPORATION OF ILLINOIS

ADJUSTABLE TERMINAL MOUNTING

Application filed December 31, 1923. Serial No. 633,572.

This invention relates to improvements in electrical switches, and more particularly to an improved contact terminal or clip mounting for switches of the disconnecting type, 5 although the invention is not limited to a particular type or class of switches nor is it limited to mounting of a particular contact making part of the switch.

In switches for opening and closing electrical circuits, particularly those for opening and closing electrical circuits carrying large quantities of current, the matter of accurately aligning the separable contacts and maintaining accurate alignment between the 10 contacts has presented a difficult practical problem. Where considerable voltages are carried, the length of the switch arm must be made relatively great for striking distance. Hence, accurate and stable adjustment of the contacts becomes of importance.

Disalignment between the contacts may either prevent closing of the contacts entirely or it may cause improper or incomplete closing. This usually results in imperfect contact and employment of only part of the conducting material in conducting the current. Where only part of the material is employed in carrying or conducting currents, which the switch is designed to carry, the circuit is subject to heating and failure, or excessive material must be employed. Accurate alignment between the contacts, even where the construction and finishing of the parts is substantially perfect, has been exceedingly difficult. It is practically impossible, for example, to avoid variation in the centering of the insulator supporting studs, where insulators so mounted are employed, and in mounting and connecting the various parts. It is 20 also difficult to avoid entirely variations in constructing and finishing the various parts. The slightest variation may disalign the contacts sufficiently to cause very objectionable results. Even if, after great labor and precision in constructing and assembling the switch, accurate alignment is secured, it has been practically impossible to maintain that alignment, after the switch has been in use for a time.

According to my present invention I pro-

vide means for adjusting the separable contacts of a switch, or similar device, to accurately line them up with each other so that proper closing and uniform contact over the entire contacting areas will be secured. The 55 adjustment provides for removing any disalignment caused by inaccuracies in construction, mounting and assembling of the apparatus or otherwise and for removing, whenever desired, any disalignment occurring 60 after use. Specifically I provide an adjustable mounting for a relatively stationary contact of the switch, but it is not limited to application to the relatively stationary contact. It may be applied to either or both of the stationary and relatively movable contacts of the switch and where both of the contacts are movable to either or both of said contacts or it may be employed for making 65 relatively stationary contacts adjustable with 70 respect to each other.

Another important aspect of the invention is the provision of an adjustable mounting which will be universal in its application to switches and insulator fittings of different 75 types and sizes. This universal characteristic of the means provided together with its simplicity, ruggedness and inexpensive construction are important, along with the broader aspects of the invention.

Another aspect of the invention is the provision of means for adjusting the contacts by a motion of translation, preferably in more than one plane and for adjusting by angular motion, preferably in any direction about a 85 point center.

Still another important aspect is the provision for securing the foregoing without moving or adjusting a great number of parts of the switch and without moving or adjusting parts of great weight or mass. This makes very accurate adjustment possible.

The adjustment provided and its universal adaptability to fittings and supports of different types and sizes are especially advantageous from a construction and assembly standpoint. Great labor and precision are not necessary, yet the most accurate alignment may be secured. The slight variations 95 100

which are usually the most difficult to remove may be readily taken care of.

In the co-pending application of Alwin G. Steinmayer, Serial No. 687,357, filed January 19, 1924, is shown an improved blade mechanism and switch in connection with which the present invention is particularly adapted for embodiment, but it is to be understood that this invention is not limited to combination with that particular blade mechanism nor to embodiment in that particular switch, but that it may be employed with any other suitable blade or contact mechanism and in various other types of switches and other apparatus.

15 Details not already referred to and the constructional features which are novel and important will appear from the following detailed description and the claims taken with an inspection of the accompanying drawings in which:

Fig. 1 is a side elevational view of a switch embodying the present invention;

20 Fig. 2 is an enlarged fragmentary side elevation of the separable contact mechanism thereof;

Fig. 3 is a section through the relatively stationary contact and adjustable support therefor on line 3-3 of Fig. 2;

25 Fig. 4 is a section on line 4-4 of Fig. 3;

Fig. 5 is a section on line 5-5 of Fig. 3;

Fig. 6 is a section on line 6-6 of Fig. 3;

Fig. 7 is a plan view of the adapted fitting employed in Fig. 1, and

30 Fig. 8 is a side elevational view of same.

In the drawings 5 designates, in its entirety, the particular switch selected for illustration. The switch itself is more fully described in the co-pending application of

35 Alwin G. Steinmayer, Serial No. 687,357, filed January 19, 1924, and forms no part of the present invention except as will be herein-after pointed out. Briefly the switch shown

40 comprises a base or slab 6. A rock shaft 7 is journaled in a bearing 8 mounted upon base 6 and mounted upon base 6 on one side of rock shaft 7 is an insulator base fitting 9 carrying an insulator 10 disposed substantially normal to base 6. The switch may, of course, 45 be mounted horizontally as shown or it may be mounted vertically or in any other desired position. Mounted upon base 6 on the other side of shaft 7 is an insulator base 11 carrying an insulator 12 disposed obliquely with

50 respect to base 6. One line conductor 13 is connected through suitable fittings on the outer end of insulator 10 to a flexible conductor 14 electrically connected at its opposite end through suitable fittings on the outer 55 end of a rocking or tilting operating insulator 15 with a movable contact or switch blade mechanism 16 on the outer end of the rocking insulator.

60 The fittings at the outer end of rocking insulator 15 are connected through suitable

linkage 15' with the fittings at the outer end of insulator 10 and rocking of shaft 7 in a counter clockwise direction, as by means of an operating link or handle 17, rocks insulator 15 and this serves to separate the movable contact or switch blade mechanism 16 from the relatively stationary terminal clip or contact 18. Rocking of insulator 15 in the reverse direction moves contact 18 into electrical contact with clip 18 and thereby closes the circuit. The particular blade mechanism 16 is more fully disclosed in the hereinbefore referred to copending application of Alwin G. Steinmayer. It comprises a pair of blade members 16' mounted on the outer end of insulator 15 and spaced to receive contact terminal or tongue 18 between and make electrical contact with the opposite sides of said tongue when the switch is closed.

65 As has already been pointed out, inaccurate alignment between contact or blade mechanism 16 and terminal clip 18 in the switch shown or between the contacts of various other types of switches and similar apparatus may either prevent closing of the contacts entirely or may cause improper closing, which results in imperfect contact and often in employing only part of the material of the contacts in carrying current. Where

70 only part of the material is employed in conducting currents which the switch is designed to carry, the circuit is subject to heating and failure and excessive material must usually be employed. As also already pointed out accurate alignment between the contacts, even where the construction and finishing of the parts is substantially perfect, is practically impossible. It is practically impossible to avoid variation in cementing the insulator 75 supporting studs in place and in mounting and connecting the various parts. It is also practically impossible to prevent variation in the construction and finishing of the various parts and even if after great labor and precision in construction and assembly, accurate initial alignment is secured, it has been practically impossible to maintain that alignment 80 after the switch had been in use for a time.

75 In order to secure accurate initial alignment without any great amount of labor and without greater precision in constructing, finishing and assembling of the switch, and to permit adjustment of clip or tongue 18 to accurately realign it with blades 16' where they become disaligned after use, I mount clip 18 upon a clip supporting member 20. The clip or tongue 18 may be provided with an integral out-turned base 21 which base 85 constitutes a supporting member for the contact clip portion 18 integral therewith, said base being secured upon member 20 by a bolt 22 or it may be mounted upon member 20 in any other suitable or preferred manner. A number of apertures 22' permit different

positions of the clip and adapt member 22 for supporting clips of different types and sizes. The details of the mounting of clip 18 upon member 20 may of course be varied as desired, as may the details of contact mechanism 16 and the other details of the switch. Supporting member 20 is preferably molded or cast with a supporting or clip mounting upper wall 23 and with integral side walls 24 depending from the edge of wall 23 and provided at their lower edges with integral equally spaced radially extending lugs 25. Each lug 25 has an aperture 26 and formed integral with and depending from the under 15 surface of each lug is a foot 28. The lower ends of feet 28 are finished to conform to a spherical seating surface 30 formed integral with and raised from a triangular flange 31 at the upper end of a supporting pedestal 32. 20 Each corner of flange 31 is apertured at 33. Bolts 35 extending through apertures 26 and 33 and engaging in suitable nuts, clamp supporting member 20 with its feet in engagement with seating surface 30 and lock the supporting member securely in place upon the spherical seating surface 30 of pedestal 32. It is to be noted that supporting member 20 is adapted for universal adjustment about seating surface 30 and feet 28 with their complementary ends cooperating with the seating surface, support member 20 with its mounting base 23 and the terminal or contact clip 18 carried thereby, firmly in any adjusted position. By loosening the nut on either one 35 or more of the bolts 35 and tightening up the other one or more nuts, supporting member 20 may be quickly and conveniently adjusted over spherical surface 30 into any desired position. Where after setting up the switch 40 it is found that contacts 16' and 18 are not accurately aligned or where disalignment occurs after use, adjustment of contact supporting member 20 in this manner permits accurate lining up of the contacts. Adjustment of supporting member 20 laterally to either side with respect to blade mechanism 16 permits removing any inaccuracy in lateral alignment, while adjustment of member 18 in a direction along the length of the blade 45 mechanism adjusts the position of contact 18 in that direction. Oblique adjustment of member 20 adjusts the position of contact 18 laterally and also in a direction along the length of the blade mechanism 16. 50 The radius of curvature of surface 30 is preferably relatively short, so that as great as possible a range of tilting of contact 18 with reference to its supporting insulator in adjustment of the contact over surface 30 is secured. Relatively slight adjustment of supporting member 20, however, usually permits the range of adjustment required for all practical purposes and tilting of the contact is not appreciable in such cases. The

range of adjustment may, of course, be as great as desired.

Molded or cast integrally with the opposite end of oblique pedestal 32 is a mounting or base flange 40 having four equally spaced bolt apertures 38 and two diametrically opposite slots or elongated bolt apertures 39. In Figures 1 and 3 pedestal 32 is shown mounted upon the upper flange 42 of an adapter fitting 43, base flange 40 being rigidly secured or clamped to flange 42 by bolts 44 shown extending through slots 39 and elongated apertures or slots 45 in flange 42. Elongation of openings 39 and 45 permit variation in positioning of bolts 44 such as might result from inaccuracies in finishing and assembling. The elongation of these openings also permits use of the adapter with pedestals of different sizes and of the pedestal with adapters of different sizes. Upper 55 flange 42 of adapter 43 also has four openings 46 which with slots 45 provides clamping openings for register with other arrangements of clamping openings in various other standard and other fittings. This makes the 60 adjustable contact support universal in its application to fittings of different styles and sizes.

Adapter fitting 43 has a base flange 48 and in Figure 1 the adapter is shown mounted upon a fitting 49 on the upper end of insulator 12 with flange 48 clamped or otherwise suitably secured to fitting 49. Base flange 48 has four equally spaced slots or elongated openings 50, four outer apertures 51 and four inner apertures registering with the apertures 46 of upper flange 42. These provide bolt receiving apertures for receiving practically any arrangement of bolts so that the adapter is thereby adapted for 100 mounting universally upon different sizes and styles of insulator fittings. In Figure 1 I have shown it mounted upon one type of fitting 49. In Figure 2 I have shown it secured by bolts 54 to a circumferential segmental 105 band type fitting 55 on the upper end of insulator 12.

The switch shown has an arc horn 56 carried by and movable with insulator 15 and a cooperating arc horn 57 carried by the supporting base or pedestal 32 and cooperating with horn 56 to protect the terminal tongue and blade members of the switch against the action of arcing as well understood in the art. The lower end of arc horn 57 is turned 115 out and back to lie in angle grooves 58 in lugs 59 formed integral with and projecting in spaced pairs from opposite sides of the connecting web 60 between flanges 31 and 40 of pedestal 32. Clamping straps 65 having supplemental angle grooves 63 are clamped across the turned out and turned back portions respectively of the arc horn 57 and are drawn together by bolts 64. The out and back turned portions of the arc horn 120

- lie partially in grooves 58 and partially in grooves 63 and the drawing together of straps 62 clamps them firmly in place therein, the angle formation of the grooves wedging into snug engagement with the horn as the straps are drawn together. Straps 62 are arranged between the pairs of lugs 59 so that said lugs will not interfere with drawing the straps together.
- 10 Projecting from one side of pedestal 32 is an integral arm 66 having at its outer end an enlarged head 67 provided with an angle groove 68. A strap 69 has a similar angle groove 70. Line conductor 71 at a distance 15 from its end lies between head 67 and strap 69, partially in groove 68 and partially in groove 70 and strap 69 is clamped over the conductor and secured to head 67 by bolts 72. As in the mounting of the arc horn the angle 20 formation of grooves 68 and 70 results in wedging into snug engagement with the insulating sheath of the conductor for example as the strap is clamped thereover. The end of conductor 71 extends on and is connected 25 with a terminal socket 73 secured to a strip 74 mounted under one or more of bolts 22.

Recapitulating briefly, the important aspects of the present invention are the provision of means for adjusting one or more of the 30 separate contacts of a switch or similar device to accurately line them up; the provision of a universal adjustment of this sort; the provision of a mounting for one of the contacts through which the adjustment is secured; and the provision of a contact mounting which is universal in its application to 35 different sizes and styles of insulator fittings and which will receive and support different arrangements as well as different sizes and 40 styles of terminal contacts. I have shown the invention in connection with the relatively stationary terminal of a particular switch and although especially adapted as an adjustable mounting for such a terminal it is not limited 45 to such use but may be embodied in either or both the relatively movable and relatively stationary contacts of the switch.

The elongation of openings 39 and 45, in addition to permitting variation in positioning of bolts 44 and permitting the combination of parts of different sizes, permits adjustment of the pedestal and the contact carried thereby by a motion of translation in the direction of the lengths of said openings. This 55 permits adjustment of the contact clip by a motion of translation in one plane. Adjustment of the clip by motion of translation in other planes is permitted by the clip mounting apertures 22' and by the elongation of 60 openings 50 in the base flange of adapter 32.

The adjustable mounting is such that adjustment is secured without adjusting the position of insulator 12, for example, and without adjusting a great number of other parts 65 of great weight or mass. The adjustment is

secured at the base of the contact clip itself and great accuracy and convenience of adjustment are secured.

I claim:

1. In combination, a pedestal having a spherical seating surface and means for mounting same upon a support, a contact carrying member having complementary supporting means adjustably seated upon said surface, a contact carried by said contact carrying member, apertured lugs on the pedestal and contact carrying members and bolt means extending through said apertured lugs for clamping the contact carrying members in adjusted position upon the supporting pedestal. 75

2. In a device of the class described, the combination of a supporting pedestal having a spherical seating surface, a mounting flange universal in its application to supports of different sizes, and a connecting web between the mounting flange and spherical seating surface, said pedestal having grooved lugs on said connecting web and a projecting arm having a grooved head, a contact supporting member adjustably seated upon the spherical seating surface of the pedestal, a contact on said supporting member, said contact having a terminal carried by the contact supporting member, a conductor clamped in the grooved head of the projecting arm of the pedestal and connected to said terminal, and an arc horn clamped in the grooved lugs of the pedestal. 95

3. In combination, a pedestal having a spherical seating surface and means for mounting same upon a support, a contact carrying member having complementary supporting means adjustably seated upon said surface, a contact carried by said contact carrying member, a plurality of openings in said carrying member and means for securing said contact at one of said openings. 100

4. In a switch, in combination, a pair of contacts, and means for permitting angular adjustment and adjustment by a motion of translation in a plurality of planes of one of said contacts relative to the other contact. 110

5. In a switch, the combination of a supporting member having a plurality of equally spaced radially extending lugs having apertures therein, a foot integral with and depending from the under surface of each of said lugs, a spherical seating surface raised from a polygonal flange member, an aperture in each corner of said flange, the lower ends of said feet being finished and adapted to cooperate with said spherical seating surface, and bolt means extending through the apertures in said lugs and flanges for locking the supporting member in place upon the spherical seating surface. 115

6. In a switch, in combination, a pair of relatively movable contacts, means for angularly adjusting one of said contacts relative to 120

the other contact about a point center, means for locking said contact in angularly adjusted position, and means for adjusting said contact by motion of translation and at an angle 5 to the relative movement of the contacts after said contact has been locked in its angularly adjusted position.

7. In a switch, a pair of contacts, one contact being relatively fixed, a switch arm pivoted to engage said contact, means for adjusting said contact angularly about a spherical center, and means for adjusting said contact by motion of translation in two dimensions. 10

8. In a switch, a pair of contacts, one contact being relatively fixed, a switch arm pivoted to engage said contact, means for adjusting said contact angularly about a spherical center, means for adjusting said contact by motion of translation in two dimensions, and means for locking said contact 15 in adjusted position.

9. In a switch, two serially positioned supports having slotted companion lugs, the slots in the lugs of one support being angularly displaced with respect to the slots in the lugs 20 of the other support, and a contact rockably mounted on one of said supports.

10. In a switch, two serially positioned supports having slotted companion lugs, the slots in the lugs of one support being angularly displaced with respect to the slots in the lugs of the other support, a third support 25 rockably mounted on one of said supports, and a contact adjustably mounted on said third support.

In witness whereof, I hereunto subscribe my name this 30th day of November, 1923.

ALFRED F. C. LOTZ.
